UNITED STATES PATENT OFFICE.

AUGIE L. HANSEN, OF EVANSTON, ILLINOIS, ASSIGNOR TO A. L. HANSEN MFG. CO., OF CHICAGO, ILLINOIS, A CORPORATION OF ILLINOIS.

ACETYLENE GENERATOR.

Application filed May 22, 1920. Serial No. 383,374.

To all whom it may concern:

Be it known that I, AUGIE L. HANSEN, a citizen of the United States, and a resident of Evanston, in the county of Cook and

5 State of Illinois, have invented certain new and useful Improvements in Acetylene Generators, of which the following is a specification.

My invention relates in general to acetylene lamps for all purposes, but is particularly designed to meet the requirements of acetylene lamps used by miners (generally known as miner's cap lamps) and to overcome the recognized disadvantages of lamps 15 of such type.

The component parts common to acetylene lamps generally are the carbide container, the water container, the burner tip, and water feeding means from the water compartment to the carbide compartment.

Water feeds in miners' lamps have been of two types; the wick feed and the hydrostatic or gravity feed.

In the drawings, which present an illustrative embodiment of the invention, which latter is not confined to the particular form disclosed:

Fig. 1 is a side elevation of the miner's lamp constructed in accordance with my invention,

Fig. 2 is a plan view thereof,

Fig. 3 is a cross sectional elevation on the line 3—3 of Fig. 1,

Fig. 4 is a cross sectional plan view on the line 4—4 of Fig. 3,

Fig. 5 is an elevation of the lower part of the wick tubes, and

Fig. 6 is a perspective view of the wick.

I provide an upper section of the lamp, 40 comprising the water chamber 1 into which the carbide chamber 2 is adapted to be screwed from beneath; the water chamber 1, being provided with a threaded recess in its bottom to receive the threaded neck 4 of the carbide chamber 2; the rubber gasket 5 forming a seal. Water being fed from the water chamber 1 to the carbide chamber 2 generates gas which passes upwardly

45 through the filter 6 along the passage 7 and out of the burner tip 7^a; this general type 50 of construction being well known in the art.

I shall now describe the means for feeding water to the carbide, the mechanism being the crucial point of a lamp of the character described.

I provide a pair of wick tubes 8 (Fig. 3), 55 extending above what would ordinarily be the top of the water chamber, and into a special cap 9 which will later be more specifically described. These tubes pass downwardly through the bottom of the water chamber and, lying side by side, extend well toward the bottom of the carbide chamber, where they are provided with an enlarged head 10, whose function will be later described. A clip 11 secured to the tubes 8 holds the plate 12 which supports and protects the filter 6 as shown.

At the upper end of the tubes 8, (which are there spaced apart) and supported thereby, is a block 13 having an upstanding journal portion 14, in which is journalled the wick-pulley 15, having a peripheral groove and a series of transverse notches as shown, the whole being housed in the cap 9, previously referred to.

The wick, housed by the wick tubes, is cruciform, comprising (Fig. 6) two long delivery branches 16, and two shorter take-up branches 17. The branches 16 are passed 60 downwardly through the tubes 8, the central portion of the wick being engaged with the pulley, with branches 17 fitting into the notches in the pulley (Fig. 3). This provides a firm engagement of the wick with the pulley. The take-up branches 17 are weighted as with lumps of lead 18, and are dropped into the water chamber where the weights cause them to extend to the lowest 65 part of that chamber (Fig. 3). This insures that a long section of the take-up branches 17, is at all times immersed in the water.

The delivery branches 16, feed the water to the carbide, and are extended through the wick tubes 8, extending for a substantial 70 distance beyond the ends thereof.

It will be apparent that, since carbide has great absorptive powers of water, the water will be sucked up by the take up wicks 17, and delivered to the carbide by the delivery 75 wicks 16, by capillarity, and that this operation will proceed uniformly regardless of 80

hydrostatic pressure, unless "back suction," clogging of the wicks or other difficulty interfere. By "back suction" I mean a condition wherein there is a large excess of pressure in the carbide chamber over that in the water chamber, which of course either stops or impedes the feeding of water to the carbide.

I shall now describe the means whereby 10 such interference is prevented, beginning with the sealing of the water chamber and its significance.

The term sealing is here used to indicate that the water chamber is sealed, or rendered 15 substantially air tight, except of course for its communication with the carbide chamber, in contrast, for instance, to the lamps heretofore in use, wherein a vent is provided in the top of the water chamber.

20 I have several times mentioned the cap 9 which encloses the pulley 15. This cap is hinged by means of an arm 20 to the bracket 21 forming a part of the lamp, and is provided with a tapering hollow stopper 22, which may be wedged home in the rubber gasket 23, mounted in a central aperture in the top of the water chamber. The tubes 8, extending upwardly into the cap, cannot be flooded, since they project upwardly beyond the top of the water chamber. The water chamber can thus be filled as full as possible (through the aperture closed by the cap 9) without bringing the water level above the tops of the tubes 8. Furthermore 30 the cap 9 through the sealing to the water chamber, also provides a safety release, because upon the development of heavy pressures, obviously the cap can be blown open, being held closed by frictional engagement 35 with the gasket 23.

When the cap is in closed position as shown in the drawings the water chamber is sealed. The sealed water chamber operates to prevent a "back suction". It does this 45 in two ways, first by building up a counter pressure in chamber 1, through the expansion of the air therein and the development of vapor as the lamp becomes heated in use, and second because any excess of pressure in 50 to carbide chamber is immediately relieved because gas can pass up the tubes 8 around the wick therein. Thus the pressure in the carbide chambers cannot become so much greater than that in the water chamber as 55 to prevent the operation of the water feed.

All of the objectionable results of a hydrostatic feed are entirely obviated in the first place by the use of a wick feed which is comparatively insensitive to variations in pressure and which feeds uniformly irrespective of the hydrostatic pressure, and in the second place by the provision of a substantially balanced pressure in the water chamber and the carbide chamber through the use of a 65 sealed water chamber.

I shall now describe the means herein provided for preventing the clogging of the wick, a difficulty which by itself has heretofore prevented the successful use of wick feeds.

In the first place, the take-up wick branches 17 feed from the cleaner top and not from the bottom of the water, and obviously a long length of these wicks is always wet by water particularly as the 70 water is splashed about, when the lamp is in use. Thus the clogging of the upper portion of the wick is effectively prevented. In order to prevent the clogging of the tubes or the portions of the wick in the tubes by 75 small particles of sediment or the like, I make use of the pulley construction above described. Thus (referring to Figs. 3 and 80 5) it will be apparent that the carbide chamber having been removed, the knotted ends 85 24 and 25 of the wick 16 can be alternately pulled, forcibly drawing the wicks 16 back and forth through the tubes 8 and over the pulley 15, thus cleaning the wicks and clearing the tubes. This can conveniently be 90 done as often as desired, and will serve effectively to prevent the clogging of the wicks.

I shall now describe the means whereby the wicks are made efficiently to communicate water to the carbide. As shown in the 95 drawings Fig. 3 the lower ends of the wicks 16 project for a considerable distance out of the tubes 8, thus exposing so much wick-surface to the carbide, as to insure the flow of the water to the carbide even if certain 100 portions of the wick become encrusted or clogged. In order more efficiently to bring the wicks in contact with the carbide I provide the enlarged head 10 previously referred to which is cone shaped and covers 105 an area larger (transversely) than the width of the two tubes 8, (at right angles to the plane of the drawing). Immediately above the head 10 are the ports 26, out of which the wick ends 16 project. These ports are 110 shielded by the head 10. When the carbide container 2 is applied to the lamp the head 10 will be driven down forcibly into the carbide and the wicks carried downwardly 115 therein. During this operation and the subsequent swelling of the carbide (which substantially doubles in volume during the 120 operation of the lamp) the wedge formation of the head 10 serves effectively to throw the carbide around and over on the top of the wicks 16, thereby insuring complete superficial contact of these wicks with the carbide. Furthermore the swelling of 125 the carbide causes the same to crowd past the wedge shaped head 10, which spreads and disturbs the carbide as it swells, assisting in the prevention of a choked or clogged condition. This action and the very substantial length of the wicks in contact with the carbide assist in making the wick feed 130

operate with substantially perfect regularity. It is to be noted also that since this lamp comprises a sealed water chamber it may be shaken violently if desired to break 5 up the carbide and distribute it about the ends of the wicks, though this operation is not necessary.

In summary, therefore, I have provided a wick feed type of lamp, wherein the water 10 is fed upwardly through wicks to a point above the water level in the water chamber and then downwardly to the ends of wicks extending for a considerable length into the carbide. I have provided a substantially 15 balanced pressure in the lamp whereby the feed of the water is rendered uniform not only by use of the most uniform type of feed, namely the capillary feed, but also by the fact that there are no substantial variations in pressure between the two chambers. In this respect the lamp is completely distinguished from the hydrostatic feed type. I have furthermore established the feed from the cleaner top water in the 20 water chamber; provided means whereby the wicks may be cleaned and the passages cleared effectively as frequently as desired; provided means ensuring the proper absorption of the water by the carbide; and 25 otherwise eliminated difficulties due to clogging of the wicks.

In Fig. 6 is shown a convenient attachment for the wick, comprising wires 28, which are bound around the ends of the 30 delivery branches 16 and extend therefrom a length greater than the length of the tubes 8. By means of these wires new wicks may quickly be passed through the tubes 8, after the wick is introduced the wires 28 35 may be stripped off and the ends 16 knotted as shown in Figs. 3 and 5.

Referring to the construction of the lamp casing (Figs. 1 and 2), I construct the reflector 30 separately. This reflector is held 40 in position between two forked extensions 31, from the U-shaped band 32, which is secured by screws 33 to the median portion of the lamp. To the rear of the band 33 45 is secured the usual hook 34 and also at the rear of the band 33, is the upward integral extension 21, carrying the hinge for the cap 9, previously referred to, and the downward spread fingers 35 of the usual type. The reflector 30 has a central aperture 50 through which is screwed the burner tip.

The lamp herein described has proved to be of efficiency superior to the hydrostatic feed, in economy of operation, elimination of the sputtering or "spitting" of water 55 from the vent, steadiness of flame and other important respects.

Having described my invention, I claim:

1. In a gas generator, the combination 60 with a receptacle for gas generating substance, a liquid receptacle, a tube extend-

ing into and communicating with said substance receptacle at its lower end, and terminating at its upper end above said liquid receptacle, a wick mounted in said tube and having an end depending into the liquid 70 receptacle, and a closure surrounding the end of said tube and forming an air chamber communicating with said liquid receptacle.

2. In a gas generator, the combination of 75 a water receptacle, a carbide receptacle below said water receptacle, a tube depending into said carbide receptacle, and extending upwardly through said water receptacle, the same having an opening in its top wall, a 80 closure for said opening forming an air chamber surrounding the end of said tube, and a wick in said tube having one extremity adapted for immersion in the water of 85 said water receptacle.

3. In a gas generator, the combination of 90 a water receptacle, a carbide receptacle below said water receptacle, a tube extending downwardly through said water receptacle and opening into said carbide receptacle, the upper end of said tube terminating within an air chamber located above the water 95 receptacle and communicating therewith, and a wick mounted in said tube, having a loose end depending into said water receptacle.

4. In a gas generator the combination of 100 an upper and lower receptacle, a pair of tubes projecting into the lower receptacle and terminating adjacent the top wall of said upper receptacle, a wick mounted in 105 said tubes having its ends extending from the lower ends of the tubes, and an intermediate looped portion extending from the upper ends of the tubes, and a branch wick 110 connected with said looped portion and depending into said upper receptacle.

5. In a gas generator, the combination of 115 an upper water and lower receptacle, a double tube connecting said receptacles, one end projecting into the lower receptacle, and the other end terminating adjacent the top of said upper receptacle, a wick mounted in 120 said tube, with its ends projecting from the lower end having an intermediate looped portion extending from the upper end of said tube, and a rotative supporting member engaging said looped portion of the wick.

6. In a gas generator, the combination 125 of an upper water receptacle, a lower carbide receptacle, a tubular member extending centrally of said receptacle, and consisting of two passages opening at their lower end to the interior of said carbide receptacle, and at their upper end adjacent the top of 130 said upper receptacle, a wick mounted in said passage, with its ends extending from the lower ends thereof, a pulley mounted at the upper end of said tubular member, and

supporting an intermediate looped portion of said work, and a branch wick extending from said looped portion into said water receptacle.

5. In a gas generator, the combination of an upper liquid receptacle, a lower receptacle, a double tubular member extending centrally of said receptacles, opening at its ends in said lower receptacle, and adjacent 10 the top of said upper receptacle, a closure in the top wall of said upper receptacle, and forming an air chamber surrounding the upper end of said tubular member, and a tubular wick doubled lengthwise and inserted 15 in said member, with its ends extending into said lower receptacle, means supporting the intermediate looped portion of said wick above the upper end of said tubular member, and branch wicks connected with said 20 looped portion and depending into said water receptacle.

8. In an acetylene generator, a water chamber, an adjacent carbide chamber, a duct having an inlet adjacent the top in 25 the water chamber, and extending substantially into the carbide chamber, a wick in said duct having both ends extending substantially into the carbide chamber, beyond the outlet end of the duct, means for maintaining a median portion of the wick above 30 the maximum water level in the chamber, and an auxiliary wick connected to said portion of the wick, and depending into said water chamber.

35. 9. In a gas generator, a water chamber, an adjacent carbide chamber, ducts having inlets adjacent the top of the water chamber, and extending substantially into the carbide chamber, a wick in said ducts having both ends extending substantially into the carbide chamber, beyond the outlet end 40 of the ducts, means for maintaining the median portion of the wick above the water level in the water chamber, and supplementary wick means for feeding water from the water chamber to the said median portion.

45. 10. In a generator, and in combination, a water chamber, a carbide chamber, a double tube, having an inlet above the water chamber, and an outlet projecting substantially into the carbide chamber, a wick looped at the top of the tube and having a branch in each part thereof, the ends of said wick projecting substantially beyond the 50 outlet end of the tube, whereby the wick may be pulled back and forth, by alternately pulling its free ends, to clear the tube and clean the wick, and supplementary wick means connecting the first wick with 55 the water in the water chamber.

60. 11. In a gas generator, and in combination, a water chamber, a carbide chamber, a pair of tubes leading from a point above the water chamber and extending substan-

tially into the carbide chamber, a guide 65 mounted adjacent the upper ends of said tubes and in the plane thereof, a wick having its median portion seated in said guide, and its free ends extending substantially beyond the outlet ends of the tube, whereby 70 the wick may be reciprocated in the tubes, by pulling its ends alternately to clear the tube and clean the wick, and a supplementary wick means, having its ends immersed 75 in the water in the water chamber and connected to the median portion of the first mentioned wick.

12. In apparatus of the class described, a water chamber adapted to be seated on and secured to a removable carbide chamber, a tube projecting downwardly from the water chamber, and adapted to be buried in the carbide in the carbide chamber, an enlargement on the lower end of the tube adapted to spread the carbide when the tube is relatively forced therewith, a lateral port in the tube, a wick communicating with the water in the water chamber and projecting for a substantial length from the port, whereby as 90 the end of the tube is buried in the carbide the wick will effectively be buried thereby for a substantial length.

13. In a gas generator, the combination of an upper portion comprising a sealed water chamber, a lower portion adapted to be removably attached to the upper portion, and comprising a carbide chamber, a tube connecting said upper and lower portions, the lower end of the tube extending far enough to be embedded in the carbide, and being provided with a lateral port, and a protecting head, the upper end of the tube projecting into the water chamber, said tube comprising the only means of communication between the two chambers, a wick slidably mounted in the tube, and projecting from said port behind the head, and extending substantially beyond the tube and adapted to be buried in the carbide, said wick extending from the upper end of the tube 100 above the water level down into the water in the water chamber for a substantial length.

14. In a gas generator, the combination of a water chamber having an opening in the top wall thereof, a hollow cap adapted to fit in said opening and to form an air chamber communicating with said water chamber, a tube extending through said water chamber and terminating at its upper end within said cap and a wick in said tube having a portion depending in the said water chamber.

15. A cruciform wick for gas generator or the like comprising two crossed wick lengths, adapted to provide, when doubled in the middle, a pair of delivery branches and a pair of take-up branches, whereby water

may be taken up by the take-up branches, then communicated to, and delivered by, the delivery branches.

16. A cruciform wick for gas generator or
5 the like, comprising a pair of delivery wick
branches, each provided with a wire tip having
a free length of wire thereon, and a pair
of take-up branches, whereby the delivery

branches may be threaded through the tubes
in the lamp and connected with a carbide 10
chamber, and the take-up branches may
communicate water to the delivery branches.

In witness whereof, I hereunto subscribe
my name this 10th day of May, A. D., 1920.

AUGIE L. HANSEN.
